(57) CLAIM

The ornamental design for a recliner, as shown and described.

DESCRIPTION

FIG. 1 is a perspective view of a recliner showing my new design.

FIG. 2 is a front view of a recliner.

FIG. 3 is a rear view of a recliner.

FIG. 4 is a left side view of a recliner.

FIG. 5 is a right side view of a recliner.

FIG. 6 is a top view of a recliner; and,

FIG. 7 is a bottom view of a recliner.

The broken lines in the rear of a recliner depict stitching lines and form part of the claimed design, the broken lines in the bottom of a recliner depict portions of the recliner that form no part of the claimed design.

1 Claim, 7 Drawing Sheets

FIG. 1

FIG. 2

FIG. 3

FIG. 4

FIG. 5

FIG. 6

FIG. 7
